CLAIM

The ornamental design for a wall conforming laptop or tablet workstation, as shown and described.

DESCRIPTION

FIG. 1 is a front perspective view of a wall conforming laptop or tablet workstation showing our new design;

FIG. 2 is a rear perspective view thereof;

FIG. 3 is a front elevational view thereof;

FIG. 4 is a left side elevational view of FIG. 3, the right side being a mirror opposite image;

FIG. 5 is a top plan view thereof;

FIG. 6 is a bottom plan view thereof; and

FIG. 7 is a rear elevational view thereof;

FIG. 8 is a front perspective view comparable to FIG. 1 except showing the cabinet doors open and the hinged table surface folded out for support of laptops, tablets, printers and like workstation devices;

FIG. 9 is a front elevational view of FIG. 8;

FIG. 10 is a left side elevational view of FIG. 9, the right side being capable of being a mirror opposite image;

FIG. 11 is a top plan view of FIG. 10;

FIG. 12 is a bottom plan view of FIG. 10; and

FIG. 13 is a rear elevational view of FIG. 10;

FIG. 14 is a section view taken along line XIV-XIV in FIG. 8; and,

FIG. 15 is a section view taken along line XV-XV in FIG. 8.

The broken lines in drawing represent environmental subject matter that forms no part of the claimed design.
